(57) **CLAIM**

We claim the ornamental design for a 3D printer, as shown and described.

DESCRIPTION

FIG. 1 is a front right perspective view of a 3D printer showing the new design;

FIG. 2 is front left perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines shown in the drawings depict portions of the 3D printer that form no part of the claimed design.
